ELIOT E. FORD, OF NEWARK, NEW JERSEY, ASSIGNOR OF ONE-HALF TO HARRY A. MURRAY, OF NEWARK, NEW JERSEY.

MATCH-BOX.

1,232,910.

Specification of Letters Patent. Patented July 10, 1917.

Application filed April 22, 1916. Serial No. 92,804.

To all whom it may concern:

Be it known that I, ELIOT E. FORD, a citizen of the United States, and a resident of Newark, county of Essex, and State of 5 New Jersey, have invented certain new and useful Improvements in Match-Boxes, of which the following is a specification.

This invention relates to a match box, and is particularly adapted for holding packages 10 of matches that are usually made of paper and are held together at one end by a paper folder which has on one of its faces an ignition surface, the folder having on its other end a flap which is adapted to be normally 15 folded over the heads of the matches and slid underneath the flap that holds the ends of the matches together. These packages are the ordinary packages of matches used 20 in commerce, and they are not in themselves new, but when used in conjunction with the present match holder, they act to assist in the positive operation of the device.

The invention relates to a match holder 25 adapted to receive the packages above described, which holder has a jaw under which the fold of the match packet is slid, the match packet when in place being adapted to engage a spring fastened to the jaw so that the jaw is normally pressed down to a 30 position where it is adapted to press a match head placed underneath it so that the match head is against the ignition surface of the packet of matches. The spring is arranged so that it acts as a stop or shield to prevent 35 any lighted particles or the burning head of a match to fly back into the packet of matches to ignite the remaining matches and to more securely shield the fingers, the fingers being still further shielded by the jaw 40 itself when it is swung upward. The jaw preferably has a finger portion bent at a slight angle to give a better grip and to also form a means against which the spring bears and by means of which it is fastened.

45 The match box is preferably made of metal, and can be of different forms and in different ways, but I illustrate a match box in the accompanying drawing which shows one embodiment of the invention.

50 In said drawing, Figure 1 is a vertical section through the match box without any matches in it. Fig. 2 is a similar view but showing a packet of matches in elevation, the matches having been placed in the box

and when in position acting to give a back- 55 ing to the spring whereby the jaw is normally held shut. Fig. 3 is a top view of the match box as illustrated in Fig. 2. Fig. 4 is an end view of the match box showing a slightly modified form of body portion. 60

The body portion 10 is preferably made of non-combustible material and sheet metal is preferably employed, the sheet forming a bottom 10 of said body portion, the body portion having side walls 11, an end wall 12 and an end wall 13, the end wall 13 being high enough to act as a stop to limit the insertion of a packet of matches, and being usually short enough to permit the free and unobstructed passage of a match over 70 the ignition surface of the packet, as will be hereinafter described. A jaw is pivoted preferably to the side walls 11, said jaw comprising a plate 14 with side wings 15, the side wings 15 and the side walls 11 75 being pivotally connected by suitable pins or rivets 16. The plate 14 extends to the rear of the pivot to a material extent and preferably has an upturned lip 17. A spring 18 is secured to the jaw, one manner of se- 80 curing said spring in place being to rest its end against the under side of the lip 17, and fasten it by any usual means, such as soldering or the like, or it can be fastened by clips or teats 19 which are integral with 85 the lip 17 and are bent over the edge of the spring 18 to hold it in place. The lower end of the spring 18 is preferably curled as at 20 to prevent its catching on the packet of matches when the packet is either in- 90 serted or withdrawn. When the box is empty the jaw can swing freely, as will be evident from an inspection of Fig. 1, the spring being under no strain and thus being relieved of any function unless a packet of 95 matches is inserted. The packet of matches is of the usual kind, consisting of a folder comprising a back 21 having a comparatively short fold 22 on its end, which flap is fastened to the back 21 by staples or in 100 any other usual manner, said staples passing through the ends or butts 23 of the matches 24, the back of the folder 21 being folded over to form a top flange or cover 25. The packet of matches is inserted in the box 105 from the rear, that is, it is inserted underneath the spring 18 from the large or higher end of the match box and the thickness of

the packet is such that the end of the packet represented by the folded part 22 engages the spring 18 and forces the spring to yieldingly swing the jaw to the position shown in Fig. 2, this being accomplished because the end of the spring terminates short of the plane of the pivot 16 so that the spring tension on the rear end or finger end 17 of the jaw 14 is upward and the other end is 10 pressed downward. The swinging end of the jaw is above the ignition surface 26 which is placed on the top face of the folded part 22 of the packet of matches.

When a match is to be ignited it is torn 15 from the packet, the match box is held in one hand, the thumb of which presses down on the finger-piece or lip 17, which pressure overcomes the spring 18 and the jaw is raised to permit the head of the match to rest on the ignition surface 26, and when the finger-piece is released the jaw 14 firmly engages the head of the matches so placed, and when a match is pulled longitudinally from between the jaw 14 and the ignition surface 26 20 it is lighted, the passage of the match being easy because the end wall 13 is short enough to prevent its interfering with the withdrawal of the match from its lighting position. The spring 18, and particularly its folded end 20, extends substantially the full width of the jaw 14, being brought close up to the side walls 15, and in this way a transverse wall or shield is provided to prevent any heads that happen to come off or burning detached particles of the heads from flying back underneath the jaw and igniting the other matches in the packet if the flap 25 had been left open in the lighting operation. It will thus be seen that the spring 25 30 has more than one function, is put under no strain, except when it is actually resting on a packet of matches in the match box, and it positively operates to hold the jaw in a normally closed position when a packet 35 of matches is in place. When a packet of matches has been used up, the folder or inclosing part of the packet can be removed from the match box, since the curled or rounded end 20 of the spring does not obstruct or hinder the withdrawal of the 40 packet.

In Fig. 4 I show a slight modification illustrating one form of packet which has an ignition surface 27 on the bottom face instead of the top face of the folded part 22 of the packet of matches, access to said ignition surface being possible by reason of the bottom 10 of the body portion being cut away as at 28.

60 It will be evident that the particular arrangement of the parts need not necessarily be as illustrated in the drawing in this application, and whether the jaw is on the top or on the bottom of the body portion is immaterial so long as it is in a position to

cover the ignition surface when in its normal position so as to protect it from wear and dirt and to uncover said ignition surface when removed or tilted from its normal position.

While the jaw and the spring are shown and described as being fastened together, it will be evident that they can be made integral, and the rear end of the jaw if folded back upon itself and arranged to project downward toward the bottom of the body portion will act substantially the same as when the device is made of two separate pieces.

Having thus described my invention, I claim:

1. A match box comprising a bottom and side walls, a jaw pivoted in said side walls, said jaw having an extension in rear of its pivot, said extension forming a thumb-piece, and a spring secured to said thumb-piece and extending downwardly and forwardly whereby said spring is without tension when the box is empty and is supplied with tension by a package of matches when such package is inserted in the holder.

2. A match box comprising a body portion to receive a package of matches, a jaw swinging on the body portion, the package of matches being adapted to have its ignition fold underneath the jaw when the package is in place, and a spring fastened to the jaw and depending therefrom in rear of its pivot, whereby the spring is given a tension to yieldingly hold the jaw shut when the package is in position.

3. A match box comprising a body portion having an open top to hold a package of matches, the body portion having side walls, a jaw hinged to the side walls, and a spring fastened to the rear end of the jaw and depending therefrom in the path that must be pursued by a package of matches when it is inserted in the holder, said spring being normally without tension but being supplied with tension by engagement of a package of matches when said package is in place.

4. A match box comprising a body portion having an open top, a jaw swinging on said body portion, the body portion being adapted to receive a package of matches of the usual kind with an ignition surface underneath said jaw, and a spring depending from the rear portion of said jaw and extending substantially across said jaw in order to engage the package of matches to form a shield and to give a tension to the spring to normally hold the jaw shut.

5. A match box comprising a body portion having an open top, a jaw hinged to the side walls of the body portion and having a lip at the back thereof, and a spring approximately as wide as the jaw and depending therefrom, said spring having a curled lower end and being long enough to be engaged by

a packet of matches inserted in the holder whereby the spring is given a tension to yieldingly hold the jaw shut.

6. A match box comprising a body portion
5 adapted to hold a packet of matches, a tilting jaw above one end of said packet of matches which contains an igniting surface, and a shield on said jaw adapted to be pressed in engagement with the packet of
10 matches when said jaw is swung to uncover the ignition surface.

7. A match box comprising a bottom and side walls, a jaw pivoted in the side walls and having an extension in rear of said pivot, and a spring of substantially the same 15 width as the jaw, said extension forming a thumb-piece and also a means whereby said spring is secured at its rear end to the jaw.

In testimony that I claim the foregoing, I hereto set my hand, this 20th day of 20 April, 1916.

ELIOT E. FORD.
